UNITED STATES PATENT OFFICE

FRANK BAUMAN, OF HONESDALE, PENNSYLVANIA

FLYER MOUNT

Application filed September 25, 1928. Serial No. 308,233.

The invention relates to twisting mechanism for spinning machines and provides a flyer and mount of unique structure capable of being cheaply manufactured, and which is light and adapted to be retained upon the spindle when applied thereto without liability of displacement.

The invention consists of a hollow metal holder, a filler therein of soft rubber or analogous material, a sheet metal retainer, interengaging elements, such as interfitting collars, between the retainer and holder, and a two armed flyer mounted upon the retainer and held thereto by means of ears partly cut from the retainer and bent about the flyer.

While the drawing illustrates a preferred embodiment of the invention, it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawing hereto attached, in which:—

Figure 1 is an elevational view of a bobbin and spindle of ordinary construction, and a flyer embodying the invention in cooperative relation therewith.

Figure 2 is an enlarged sectional view of the flyer and mount and a portion of a spindle, the outer ends of the arms of the flyer being broken away.

Figure 3 is a horizontal sectional view on the line 3—3 of Figure 2 looking in the direction of the arrows.

Figure 4 is an enlarged, fragmentary sectional view on the line 4—4 of Figure 3.

Corresponding and like parts are referred to in the following description and designated in the several views of the drawing by like reference characters.

The numeral 1 designates a spindle and 2 a bobbin mounted thereon. These parts may be of any well known construction and are illustrated to demonstrate the application of the invention which resides in the flyer and

parts associated therewith and forming the mount.

The numeral 3 denotes the holder which is hollow and formed of sheet metal pressed or otherwise shaped substantially as illustrated. 55 The holder is of circular outline and formed on its upper side with a collar comprising portions 4 and 5, the part 4 being constricted and the part 5 outwardly bulged. An insert 6, preferably of soft rubber, is fitted within the body portion of the holder and is formed centrally with an opening to receive the spindle 1, upon which it is held by frictional engagement of the insert 6 therewith.

A retainer, comprising a sheet metal plate 65 7, has a collar 8 pressed laterally therefrom and outwardly bulged to snugly receive the outwardly bulged portion 5 of the collar on the holder whereby to secure the part without any binding action so that the retainer is 70 free to rotate. As shown most clearly in Figure 2 of the drawing the retainer is elongated or elliptical in outline and ears 9 are partly cut from opposite end portions and pressed laterally and bent to engage about the middle portion 10 of the flyer adjacent the inner ends of the arms 11.

In this manner the flyer is secured to the retainer without necessitating the provision of extraneous fastening means. The interfitting of the elements 5 and 8 prevent displacement of the retainer while admitting of its free rotation upon the holder which is held upon the spindle 1 by means of the filler 6. 85

Having thus described the invention, I claim:—

1. A flyer mount for a bobbin spindle comprising a holder having a central opening, and having a collar upon its top side in line with the opening, said collar having a portion outwardly bulged, a rubber insert in the holder to secure the flyer on the spindle, and a retainer loose on the holder having a collar on its bottom side outwardly bulged to receive the corresponding outwardly bulged portion of the holder collar. 90

2. A flyer mount for a bobbin spindle comprising a plate having a spindle receiving opening and a collar in line with the opening 130

and outwardly bulged, and having ears partly cut therefrom, a flyer having its middle portion curved to embrace the collar between the outer bulge thereof and the plate and held in place by the ears bent therearound adjacent the ends of the curved portion, a holder loosely supporting the said plate, and inter-engaging means between the plate and holder to maintain them in assembled relation.

10 3. A flyer mount for a bobbin spindle comprising a hollow holder in which is formed a central opening, and having a collar on its top side in line with the opening and outwardly bulged, a packing insert within the holder, a plate having a spindle receiving opening and a collar in line with the opening and outwardly bulged to receive the bulged portion of the holder collar, and having ears 15 partly cut therefrom, and a flyer having its middle portion curved to embrace the collar and held in place by the said ears which are bent therearound adjacent the ends of the curved portion.

20 25 In testimony whereof I affix my signature.
FRANK BAUMAN. [L. S.]
